UNITED STATES PATENT OFFICE.

WILLIAM HINKELMAN, OF ALBANY, NEW YORK.

BAG FOR HOLDING HAMS.

SPECIFICATION forming part of Letters Patent No. 683,760, dated October 1, 1901.

Application filed June 15, 1901. Serial No. 64,668. (No model.)

To all whom it may concern:

Be it known that I, WILLIAM HINKELMAN, a citizen of the United States of America, and a resident of the city and county of Albany, 5 State of New York, have invented certain new and useful Improvements in Bags for Holding Hams, of which the following is a specification.

My invention relates to devices for retaining hams during the process of boiling; and the object of my invention is to provide a bag within which a ham may be placed and securely retained in position therein without changing the normal contour of the ham and 15 which may be securely fastened, preventing moisture from penetrating the bag through the openings therein, together with such features as shall be hereinafter more particularly pointed out and claimed. I accomplish 20 this object by means of the mechanism illustrated in the accompanying drawings, in which—

Figure 1 is a plan; Fig. 2, a plan showing a ham placed in the bag with two of the flaps 25 drawn together, and Fig. 3 a plan showing the bag with the ham placed therein ready for the boiling process.

Similar letters refer to similar parts throughout the several views.

I preferably construct my bag of duck canvas provided with a central portion A, adjacent to which and on each side and end I provide the flaps B, C, D, and E, respectively. I preferably cut away a portion of the canvas 35 between the flap E and the flaps B and D in order to prevent the bunching of the canvas about the shank of the ham when it is folded onto the central portion A of the bag over the ham inclosed therein. It will be 40 noted that the central portion A is preferably made narrower at one end—that is, adjacent to the flap E—than at the opposite end adjacent to the flap C, thus conforming somewhat to the usual shape of a ham, the butt-end of 45 the ham, which contains a more considerable portion of fat, being placed adjacent to the flap C.

In order that the butt of the ham shall not be crowded when fastened within the bag 50 and so that it shall maintain its normal con-

tour, I place within the flap C a stiffening substance, preferably a metal plate F, which when the flap C is brought in contact with the butt of the ham will rest against the butt of the ham and prevent the fat from being 55 drawn, when the cords holding the flaps in position are tightened, out of its normal position, and thus keeping the butt-end of the ham during the boiling process from being affected by its incasement in the bag. I likewise place in the flaps B and D stiffening substance, preferably metal plates G and H, respectively, which will prevent the sides of the ham from being drawn out of their normal position by the tightening of the cords 65 holding the flaps B and D about the ham.

I have shown the plates G and H tapering from the end nearest the butt of the ham toward the shank of the ham, for the reason that a considerable portion of the stiffening 70 of the flap is required near the fatty portion of the ham. I do not, however, limit myself to this construction of the contour of the plates G and H.

The flap E is not necessarily provided with 75 any stiffening material, since the shank of the ham will retain its normal position regardless of the strain brought upon it by the tightening of the cords.

It is understood that the metal plates F, 80 G, and H may be placed in position on the canvas and retained there by sewing a covering *c g h* over them respectively or secured in any suitable manner.

After the ham has been placed in position 85 on the central portion A of the bag, as shown in Fig. 2, a suitable cord may be drawn about the hook J on the flap E and about the hook K on the flap C, the flaps E and C being placed over the ends of the ham, and by 90 tightly drawing the two flaps together by means of the cord L, the plate F holding the butt of the ham squarely in position, the ham is securely retained, so far as the ends are concerned, in its normal position. The 95 flaps B and D are then folded over the ham and held in position by the cord M, laced about the hooks N, which are secured along the sides of the central portion A, preferably opposite each other. By securing the cord 100

after this lacing the ham is securely incased within the bag and the bag and ham assume the position shown in Fig. 3.

It is apparent that the hams may differ in size and yet be incased in my bag. It is also apparent that the length of the flaps may be so arranged that there is no opening through which the water may penetrate. The ham when taken out of my bag is, its ends and sides including the fat thereon, not affected by being broken down or bent over or overlapped by the pressure of the cords or ends of the casing as frequently in the bags now in use.

15 What I claim as my invention, and desire to secure by Letters Patent, is—

1. A bag for incasing a ham, consisting of a central portion; four flaps adjacent thereto; three of said flaps provided with stiffening

material; with means for securing the flaps 20 in position about the ham, substantially as described.

2. In a bag for incasing a ham; a piece of duck canvas provided near one corner thereof with a stiffening material, stiffening material 25 placed diagonally across said canvas, parallel to each other, and separated from each other a sufficient distance to allow a ham to be laid between them; a portion of said canvas cut away from each edge near one corner thereof; 30 all substantially as described.

Signed at Albany, New York, this 7th day of June, 1901.

WILLIAM HINKELMAN.
